Stella Maynier, Forest Hills, N. Y.

Application March 11, 1953, Serial No. 23,983

Term of patent 14 years

(Cl. D58—26)

To all whom it may concern:

Be it known that I, Stella Maynier, a citizen of the United States, residing in Forest Hills, county of Queens, State of New York, have invented a new, original, and ornamental Design for a Combined Applicator and Brush for Bottles or Similar Article, of which the following is a specification, reference being had to the accompanying drawing, forming a part thereof, in which:

Fig. 1 is a front elevational view of a combined applicator and brush for bottles or similar article, showing my new design;

Fig. 2 is a side elevational view thereof, and
Fig. 3 is a plan view thereof.

I claim:

The ornamental design for a combined applicator and brush for bottles or similar article, as shown.
